UNITED STATES PATENT OFFICE.

ANTOINE VERICEL, OF BALDWIN, NEW YORK, ASSIGNOR TO DOEHLER DIE-CASTING CO., A CORPORATION OF NEW YORK.

DESIGN FOR A RADIO LOUD-SPEAKER OR THE LIKE.

Application filed November 30, 1928. Serial No. 29,070. Term of patent 14 years.

To all whom it may concern:

Be it known that I, ANTOINE VERICEL, a citizen of the Republic of France, and a resident of Baldwin, in the county of Nassau and State of New York, have invented and produced a certain new, original, and ornamental Design for Radio Loud Speakers or the like, of which the following is a specification, reference being had to the accompanying drawings, forming part thereof, wherein—

Fig. 1 is a front view of a loud speaker, showing my new design, and
Fig. 2 is a side view thereof.

I claim:

The ornamental design for a radio loud speaker or the like, as shown.

ANTOINE VERICEL.
